Wm. J. Davis.

ATTORNEY

UNITED STATES PATENT OFFICE.

ERNEST DE WITT, OF KANSAS CITY, MISSOURI.

DISAPPEARING WINDOW-SCREEN.

1,186,293.

Specification of Letters Patent.

Patented June 6, 1916.

Application filed October 8, 1914. Serial No. 865,668.

To all whom it may concern:

Be it known that I, ERNEST DE WITT, a citizen of the United States, residing at Kansas City, in the county of Jackson and State of Missouri, have invented certain new and useful Improvements in Disappearing Window-Screens, of which the following is a full, clear, and exact description, such as will enable others skilled in the art 10 to which it appertains to make and use the same.

The invention relates to disappearing detachable screens in connection with windows of an inclosure.

15 It is essential that the screens be conveniently located so that they will always be ready for use and securely hidden when not in use.

The present invention seeks to provide an 20 improved window screen preferably mounted on a roller hidden in the casing and attached to the window when in use, and when not in use detached from the window and wound up on the roller thereby eliminating the necessity of taking down the 25 screens in the fall of the year and replacing them again in the spring of the year.

With these and other objects in view, the 30 invention consists in the features of construction and arrangements of parts hereinafter set forth, illustrated in the accompanying drawing and more particularly pointed out in the appended claims.

In the drawings: Figure 1. is a view in 35 elevation of a window and the improved screens, the screens being detached and a part of the view broken away to save room in illustrating. Fig. 2. is a view in vertical cross section of the window and improved 40 screens, taken on line *a—a* of Fig. 1, the lower sash being in closed position. Fig. 3 is a view in section taken on line *b—b* of Fig. 2. with the lower sash raised. Fig. 4. is an enlarged fragmentary view taken on 45 line *c—c* of Fig. 5 showing the catch in closed position and holding the screen to the sash. Fig. 5. is an enlarged fragmentary sectional view taken on line *d—d* of Fig. 4. Fig. 6 is a fragment of the roller 50 broken open to show the interior. Fig. 7. is an enlarged fragmentary view taken on line *e—e* of Fig. 1. showing the spring which holds the screen against the casing.

One end of the screen 1 is secured to the 55 roller 2, while the opposite end is held firmly between the ends of the sheet metal mem-

ber 3, which is formed to fit in the groove 4 of the sash 5, a slot being cut near each end of the member 3 for receiving one end of the catch 6 which is secured on the shaft 60 and mounted in the sash and turned by means of the handle 8 mounted thereon.

The roller 2 is mounted in the window casing 11, the screen passing through a slot 9 cut in the casing, and is wound on the 65 roller by the spring 10, one end of rod 12 being held securely to the casing by the bracket 13. The opposite end thereof is inserted in one end of the roller and one end of the spring is attached thereto at 14, the 70 opposite end of the spring 10 being attached to the roller by means of the staple 15. Grooves 16 are cut in the window guides 17, and one end of the flat leaf springs 18 are mounted in the grooves, the opposite end 75 being bent outward to force the screen against the guide 17 so that there will be no space between the guide and the screen, when the window is open the spring being forced back into the groove by the sash and 80 out of the way when the sash is closed.

The upper and lower sash may each be connected with the improved screen in the same manner as described so that when it is desired to open the windows and close the 85 screens the handle 8 may be turned and the member 3 locked to the window with the catch 6, by opening the window the screens which are mounted on the rollers 2 will unwind furnishing screen as needed, and 90 when it is desired to open the window and not use the screen, the latter may be released by unlatching the catches 6 from the member 3 and raising the window, leaving the screens wound on the rollers and the pieces 95 3 resting against the window casing.

I claim:

1. In disappearing window screens, a window casing comprising side members and end members, guides on said side members, sash mounted between said guides, rollers mounted in said end members, screens mounted on said rollers, springs in said rollers, said springs always exerting a force to wind said screens on said rollers, 100 a metal strip secured to each of said screens and held normally against said end members by said springs and said screens, loops extending into the window opening and secured to said metal strips, shafts mounted 105 transversely in said sash, handles securely mounted on said shafts and positioned on

the face of said sash, and semi-circular hooks mounted on said shafts within said sash and arranged to be engaged with and disengaged from said loops by the movement of said handles.

2. In disappearing window screens, a window casing comprising side members and end members, guides on said side members, sash mounted between said guides, 10 slots in the end members of said casing, an angle shaped metal strip secured to each of said screens and held normally against the respective end member, screens mounted on

the out side of said end members and passing through said slots and connecting to 15 said angle shaped metal plates, loops projecting into the window opening from said plates, and circular hooks pivoted in said sash and arranged to draw said angle shaped plates tight against said sash. 20

In testimony whereof I affix my signature in the presence of two witnesses.

ERNEST DE WITT.
